(57) **CLAIM**

The ornamental design for a pair of children's goggles, as shown and described.

DESCRIPTION

FIG. 1 is a first perspective view of a pair of children's goggles showing the claimed new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plane view thereof;

FIG. 7 is a bottom plane view thereof; and,

FIG. 8 is a usage plane view thereof.

The broken lines immediately adjacent to the claimed portions are boundaries, all other broken lines are environmental structures; all the broken lines form no part of the claimed design.

1 Claim, 8 Drawing Sheets
